NEUTRAL BAR ASSEMBLY

Salvatore Sori, Woodbury, N.J., assignor to I-T-E Circuit Breaker Company, Philadelphia, Pa., a corporation of Pennsylvania

Filed Dec. 31, 1956, Ser. No. 631,552

1 Claim. (Cl. 339—198)

My invention relates to an electrical connector for electrically connecting a plurality of electrical conductors to a common potential.

A primary object of this invention is to provide the above described type of device to be hereinafter described as a neutral bar assembly which utilizes standardized components for any required number of terminal positions and is simply and economically manufactured.

More specifically, the complete assembly is supported from a support member and comprises first and second neutral insulating bases which are of identical construction and are fastened to the support member through an insulating liner.

Each neutral base has apertures therein in identical positions, which apertures receive and support a neutral bar of conductive material. The neutral bar has means associated therewith such as terminal openings for connecting to the various current conductors which are to be connected at the same isolated potential. If desired, this neutral bar could be a tube of copper having apertures therein for receiving the conductive leads and a respective wire pressure screw appropriately positioned with respect to each of said apertures for maintaining the conductor rigidly fastened within its respective aperture.

Thus, a tube of copper having the required apertures and screw holes may be cut to lengths in accordance with the number of lead wires to be connected to a common potential. The two identical neutral bases are then positioned at either end of the bar and receiving the bar in their respective apertures to support the copper bar from the support in insulated relationship therewith by virtue of the insulating liner interposed between the bases and the support as well as by the insulating bases.

If it is desired to ground the neutral bar to the support member, it is possible to have a bonding screw protrude through and engage the neutral bar and pass through the liner into engagement with the support structure. Thus, an electrical engagement will be completed between the neutral bar and the support member by the bonding screw.

Accordingly, an important object of my invention is to provide a novel neutral bar assembly.

Another object of this invention is to provide a novel neutral bar assembly which offers simple manufacture and easy installation.

Another object of my invention is to provide a novel connecting means for connecting a plurality of current conductors to one another in a convenient manner.

These and other objects of my invention will become apparent from the following description when taken in conjunction with the drawings in which:

Figure 1 shows a perspective view of the neutral bar assembly of my invention when mounted to an enclosure wall or support member.

Figure 1a shows a perspective view of a modified neutral bar assembly of my invention.

Figure 2 shows a top plan view of the neutral bar.

2

Figure 2-A shows a side view of Figure 2 when taken across the lines 2A—2A.

Figure 3 shows a front view of the assembled device of Figure 1.

Figure 4 shows a top view of Figure 3.

Figure 5 shows a side view of Figure 3.

Figure 6 shows a front view of an embodiment of Figure 1 wherein a bonding screw serves the dual function of bonding the neutral bar to ground as well as fastening one neutral base to the support.

Figure 7 shows an electrical diagram of an application of my novel device to a single phase system.

Referring first to Figure 7, it is seen that an electrical circuit comprising the transformer 20 has a center tapped secondary winding 22 which energizes a first and second load 24 and 26 respectively through the circuit interrupting devices 28 and 30 respectively.

In some cases, the center wire 32 as well as conductor leads 34 and 36 of loads 24 and 26 respectively are connected to a common potential and this common potential is then brought to the ground potential of the ground lead 38. In order to do this, each of the conductor leads 32, 34, 36 and 38 are interconnected by means of the current carrying member or neutral bar 40.

In common practice, the circuit breakers 28 and 30 are mounted within a common enclosure as indicated by the dotted box 31, and it is desirable that wires 32, 34, 36 and 38 be connected within the enclosure as seen in Figure 7.

The essence of my invention is to construct a neutral bar assembly or an assembly for carrying the bar 40 in an insulated relationship with respect to conductive material adjacent the neutral bar and to allow a convenient method for interconnecting lead wires to be connected together within an enclosure such as the enclosure 31 of Figure 7.

A first embodiment of my novel invention is set forth in Figures 1, 3, 4 and 5 which are perspective, front, top and side views respectively.

In each of these figures the neutral bar 40 (Figures 2 and 2-A) is comprised of a tube of conductive material having apertures 42, 44, 46 and 48 therein which are adapted to receive the leads of electrical connectors and also have wire pressure screws 50, 52, 54 and 56 respectively for cooperating with their respective apertures to insure a good connection between the respective conductive leads and the neutral bar 40.

This neutral bar 40 is mounted on and supported by an enclosure wall 31 by means of the two identical neutral insulating bases 58 and 60, which are positioned at either end of the neutral bar 40, by means of mounting screws 64 and 66 respectively as is best seen in Figure 3. The neutral insulating liner 62 is interposed between bases 58 and 60 and enclosure wall 31 to provide further dielectric separation between the bar 40 and the enclosure 31, if required.

Each of the neutral bases 58 and 60 has first apertures 68 and 70 respectively, and second apertures 72 and 74 respectively therein. Each aperture, as may be best seen in Figure 5 for the case of aperture 72, is shaped to cooperate with the cross sectional shape of the neutral bar 40.

Thus, the neutral bar may be easily and simply inserted within one of the apertures 68 or 72 of neutral base 58 or apertures 70 or 74 of neutral base 60 depending upon the relative positioning of either of these bases.

In order to assemble the device, a length of neutral bar is cut in accordance with the required number of terminal positions which is given by the number of conductors which are to be connected to a common potential for a given application. This predetermined length of conductor is then inserted in the respective apertures of

neutral bases 58 and 60, and the neutral bases are fastened to the liner.

It is to be noted that neutral base 58 could be first fastened to the support 31 and have the left-hand end of neutral bar 40 inserted in aperture 72. The neutral base 60 may then be brought into position so that the right-hand end of neutral bar 40 is inserted within aperture 70 and the base 60 may thereafter be fastened in position by means of its mounting screw 66.

Clearly, the liner 62 has apertures therein to pass the required mounting screws.

Hence it is clear that my neutral bar assembly is easily adjusted to accommodate as many terminals as is required by merely using appropriate length of a neutral bar. Furthermore, the neutral bases 58 and 60 are interchangeable and are fastened to the support 31 at whatever point necessary as given by the particular length of the neutral bar 40.

If desired, it is then possible to pass a bonding screw such as the bonding screw 82, as best seen in Figure 3, and into engagement with support 31. The effect of this bonding screw 82 provides a bonded neutral and brings the potential of neutral bar 40 to the potential of the support of enclosure 31.

While Figures 3 and 4 show the bonding screw 82 as being fastened to the support 31 and positioned intermediate between fastening screws 64 and 66, Figure 6 shows that the screw 82 could be so positioned as to further serve the purpose of mounting screw 64. That is to say, bonding screw 82 could provide the bonded neutral as well as provide the fastening between neutral base 58 and the liner 62.

In Figure 1a, I have illustrated a modified embodiment of the neutral bar assembly of Figure 1. In the embodiment of Figure 1a all components corresponding to the components of Figure 1 are identified by a similar numeral with a prime. Thus, two identical bases 58' and 60' are provided to support the neutral bar 40'. The embodiment of Figure 1a differs from that of Figure 1 in that the neutral bases 58' and 60' do not require openings to receive the neutral bar 40'

since this unit is supported on top of the bases in any desirable manner.

Although I have described preferred embodiments of my novel invention, many variations and modifications will now be obvious to those skilled in the art, and I prefer therefore to be limited not by the specific disclosure herein but only by the appended claim.

I claim:

A neutral bar assembly for electrically connecting a plurality of conductors; said neutral bar assembly comprising a first and a second base of insulating material, a common member, a neutral bar, and a neutral liner interposed between said bases and said common member, a first and a second member fastening said first and said second bases, respectively, to said common member; each of said first and second bases having a first and a second opening therein; said neutral bar having a first end supported in the first of said openings of said first base and another end supported in the second of said openings of said second base; said neutral bar comprising a length of conductive material having apertures therein for respectively receiving electrical conductors and means for applying pressure between said electrical conductors and said neutral bar when said conductors are inserted in said apertures; said first and second bases having identical constructions and being interchangeable with one another; said first member comprising a rotatable screw for electrically connecting said bar to a point of predetermined electric potential; said screw being passed through cooperating apertures in said neutral bar and said first base and being terminated in said common member supporting said first and second bases.
